UNITED STATES PATENT OFFICE.

JAMES W. MENESEE, OF FORT WAYNE, INDIANA, ASSIGNOR TO THE MENESEE FOUNDRY CO., OF FORT WAYNE, INDIANA, A CORPORATION OF INDIANA.

MANGLE.

Application filed October 16, 1922. Serial No. 594,737.

This invention relates to a mangle for ironing clothing, or other articles by means of cooperating rollers and has for its object the provisions of such a device which shall be conveniently mounted and which shall be of improved construction and operation.

A further object is to provide a mangle which may be folded into a compact position and moved into a compartment provided in a wall or other suitable location, the compartment being closed by a door so that the mangle is entirely concealed when not in use.

Other objects of the invention will appear hereinafter.

The invention is exemplified in the combination and arrangement of parts shown in the accompanying drawings and described in the following specification, and it is more particularly pointed out in the appended claims.

In the drawings—

Fig. 1 is an elevation of one embodiment of the present invention shown in operative position;

Fig. 2 is a side elevation looking from the left in Fig. 1;

Fig. 3 is a top plan of the device shown in Fig. 1 with the enclosing walls and door in section;

Fig. 4 is a section on line 4—4 of Fig. 1;
Fig. 5 is a section on line 5—5 of Fig. 1;
Fig. 6 is a section on line 6—6 of Fig. 1;
Fig. 7 is a section on line 7—7 of Fig. 1;
35 and

Fig. 8 is a section on line 8—8 of Fig. 1. As illustrated in the drawings, a recess or closet 10 is provided with a door 11 pivoted to swing about an upright standard 12, the lower end of which rests upon the floor and which is provided with any suitable form of braces 13 to retain it in upright position. A frame plate 14 is secured to the standard 12 by hinges 15 and 16. The frame plate 14 carries the door 11, as shown in Fig. 3, so that the door is supported by the hinges 15 and 16 and swings with the plate 14 about the standard 12.

A guide plate 17 is secured to the frame plate 14 and carries an arcuate track 18 in which a turntable 19 is guided for rotary movement about a horizontal axis at right angles to the frame plate 14. The turntable 19 is an upright plate having a flange 20

seated in the groove formed by the track 18. The turntable 19 carries space brackets 21 and 22 which project forwardly at their upper end to support bearings 23 and 24 in which a shaft 25 is journaled. An arm 26 is secured to the outer face of the bracket 22 and supports a bearing 27 for receiving the end of the shaft 25 opposite the bearing 23. The upper mangle roller 28 is secured to the shaft 25 between the bearings 24 and 27. The lower mangle roller 29 is supported on a shaft 30 which is journaled in bearings 31 and 32 carried by arms 33 and 34, respectively which have their ends secured to a shaft 35. The shaft 35 is journaled in the lower ends of the brackets 21 and 22 and in ears 36 and 37 formed on the turntable 19. The arms 33 and 34 are pinned or otherwise secured to the shaft 35 so that they will swing in the pivotal mounting of the shaft in unison with one another.

A third arm 38 is secured to the shaft 35 and is provided with a bearing 39 through which the shaft 30 extends. The outer end of the arm 38 is provided with a pivot stud 40 which passes through an elongated slot 41, Fig. 1, in the upper end of a link 42. The lower end of the link is pivoted at 43 to a foot lever 44 which is pivotally mounted at 45 on a bracket 46 supported by the door 11. The bracket 46 carries a notched segment 47 which is engaged by a flange 48 at the upper edge of the lever 44 for holding the foot lever down in any position to which it is moved by the operator. This will exert an upward force on the link 42 and support the outer end of the arm 38, thus retaining the shaft 30 and the roller 29 in any vertical position of adjustment to which it is moved by the foot lever 44. The foot lever 44 may be moved into and out of engagement with the notched segment 47 by pressing laterally upon the foot lever, there being sufficient play at the pivotal support 45 to permit the lever to move into and out of engaged position.

In operation, the lever is released to lower the roller 29 and pressure is placed upon the lever to raise the roller when it is desired to cause the rollers to bear more closely together.

A basket 49 is pivotally connected at its rear edge to a rod 50 supported at its inner end on the bracket 21 and at its outer end by an arm 51 which is carried by the end

of the shaft 30. The arm 51 forms a portion of a supporting spider having a downwardly extending arm 52 and a forwardly extending arm 53. The arm 52 is connected by a plate 54 with a counterpart arm 55 at the inner end of the roller 29 and the forwardly extending arm 53 is also provided with a counterpart 56 at the inner end of the roller.

- 10 The arms 55 and 56 are connected with a rearwardly extending arm 57 similar to arm 51 which is connected with the rod 50 adjacent the bracket 21, as shown in Fig. 4. A table 58 is supported by the arms 53 and 15 56 in position to guide an article to be ironed between the rollers 28 and 29. The table 58 is divided into sections hinged together at 59, the front section 60 having brackets 61 which are connected by flexible straps 62 with the front edge of the basket 49, as shown in Fig. 2. When the section 60 is folded into the broken line positions shown in that figure, the basket 49 will be drawn close to the roller 29 so that the entire construction is compacted for movement into the compartment 10.

An extension plate 63 is pivoted on the rod 50 and may be swung from broken to full line positions in Fig. 2 to form a guide for 30 directing clothes into the basket 49. Secured to the shafts 25 and 30, respectively, are worm gears 64 and 65. These gears are enclosed in a split housing 66 secured to the bracket 21 and mesh with worms 67 and 68 35 carried by a shaft 69 journaled in the housing 66. The worm 67 is provided with double threads to impart a more rapid movement to the gear 64 and consequently to the upper roller 28 than is imparted to the lower roller 29, thus securing the desirable 40 slip between the two rollers for ironing the material.

The upper end of the shaft 69 carries a pulley 70 which is connected by a belt 71 45 with a pulley 72 on a motor shaft 73. The motor shaft 73 is provided at its lower end with an end thrust bearing to support the weight of the motor armature which forms a part of an electric motor 74. The motor 50 74 is carried by a bracket plate 75 struck outwardly from the turntable 19, as shown in Fig. 5. The mangle roller 28 may be heated in any usual manner and the operation 55 of the device will be readily apparent.

The turntable 19 carries a bifurcated stop 76 which engages a lug 77 on the standard 12 to hold the rollers in horizontal position and limit their downward movement during 60 operation. When it is desired to fold the device the rollers are moved in a clockwise direction into the broken line position indicated in Fig. 1. During this movement the foot lever 44 will swing upwardly 65 about its pivot 45 into an upright position,

the table 60 having been previously folded, as before described. When the mechanism is in its folded position the center of gravity will be at the right of the pivotal axis, as viewed in Fig. 1, so that it will automatically remain in this position. The door may then be closed and the entire device will be concealed within the compartment 10.

I claim:

1. A mangle comprising a pair of rollers, 75 a motor for driving said rollers, a frame plate for supporting said motor and rollers, and a track in which said frame plate is mounted to constitute a turntable for said motor and rollers, said frame plate and 80 track being arranged in upright planes to cause said motor and rollers to pivot on a horizontal axis.

2. A mangle comprising a pair of rollers, 85 an upright plate on which said rollers are mounted and having the plane thereof substantially parallel with the axes of said rollers, and a track for supporting said plate to permit movement thereof about a horizontal axis transverse to the axes of said 90 rollers.

3. A mangle comprising a pair of rollers, 95 a frame plate on which said rollers are mounted, means for supporting said frame plate and rollers for movement about a horizontal axis transverse to the axis of said rollers, and means for supporting said frame plate and rollers for movement about an upright axis, said means for supporting said frame plate and rollers for movement 100 about a horizontal axis comprising a track positioned in a vertical plane.

4. In combination, a structural body having a floor and a chamber disposed above said floor, said chamber being provided with an opening at one side thereof, a mangle, a pivotal support for said mangle fixed to said floor adjacent said opening, said mangle being movable about said pivotal support into and out of said chamber.

5. In combination, a structural body having a chamber therein provided with an opening at one side thereof, a closure for said chamber movable into and out of position to close said open side, a mangle connected with said closure and movable into and out of said chamber, said mangle being pivotally mounted on said closure to permit shifting the position thereof from horizontal operative position to vertical position for storage in 120 said chamber.

6. In combination, a structural body having a chamber therein, an upright pivot shaft secured to the floor adjacent said chamber, and a mangle mounted on said pivot shaft and movable horizontally about said pivot shaft into and out of said chamber.

7. In combination, a structural body having a chamber therein, an upright standard positioned adjacent said chamber, a mangle 130

5 mounted on said standard and movable into and out of said chamber, and a closure for said chamber, said mangle being movably connected with said closure and shiftable to a horizontal position to extend past the edge of said closure.

8. In combination, a structural body having a chamber therein, a support carried by said structural body and positioned adjacent 10 said chamber, and a mangle mounted on said support and movable thereon into and out of operative position, said support being movable to bring said mangle into said chamber, thereby closing the opening 15 to the same.

9. The combination with a door, of a mangle pivotally mounted on said door and movable into an upright compacted position substantially parallel with the vertical length 20 of said door.

10. The combination with a door, of a mangle pivotally mounted on said door and movable about an axis perpendicular to said door into operative and compacted positions relative thereto, said mangle being 25 also movable in unison with said door when said door is opened and closed.

11. The combination with a structural body having a chamber therein, of a door 30 for closing said chamber, a mangle pivotally mounted on said door, and movable relative thereto into and out of upright compacted position parallel with said door, said mangle being movable into said chamber when said 35 door is closed.

12. The combination with a structural body having a floor and a chamber above said floor, of an upright standard secured to said floor adjacent said chamber, a frame 40 pivoted on said standard, a mangle, comprising a pair of rollers, mounted on said frame for movement about a horizontal pivot, and a door connected with said frame, said door and mangle being movable about said upright standard to bring said mangle into 45 and out of said chamber and to move said door into and out of closed position.

13. In combination, a frame plate, a mangle roller journaled in fixed bearings on 50 said frame plate, a second mangle roller journaled in movable bearings, a motor for driving said rollers mounted on said frame plate, and an arcuate track having the plane thereof upright for supporting said frame 55 plate to permit movement of said rollers and motor about a horizontal axis.

14. In combination, a pair of mangle rollers, a table for directing material to said rollers, a basket for receiving material from 60 said rollers, said table and basket being movable from operative positions to compacted positions, and a connection between said table and basket to cause said basket to move in unison with said table.

65 15. In combination, a pair of mangle

rollers, a table for directing material to said rollers, a basket for receiving material from said rollers, said table and basket being foldable into compact position relative to said rollers, a support for said rollers, and a pivotal connection between said rollers and support to permit said rollers, table and basket to be moved into a compacted position when not in use.

16. In combination, a pair of mangle 75 rollers, a motor for driving said rollers, a table for directing material to said rollers, a basket for receiving material from said rollers, said table and basket being foldable relative to said rollers into a compact position, a support for said motor, rollers, table and basket, and a pivotal connection between said mangle parts and said support to permit said parts to be folded relative to said support into a compacted position.

17. In combination, a structural body having a floor and a chamber above said floor, an upright standard engaging the floor of said chamber body positioned adjacent said chamber, a supporting plate pivotally mounted on said upright standard, and a mangle carried by said supporting plate and comprising a pair of rollers pivotally mounted on said plate for movement into a horizontal operative position and into an upright compacted position, said support being movable about said upright standard to bring said mangle into position within said chamber while said rollers are in upright compacted position.

18. In combination, a structural body having an upright standard positioned adjacent thereto, a frame member mounted on said standard, a mangle comprising a pair of rollers carried by said frame member and movable thereon into horizontal operative position and into upright compacted position, a motor for driving said rollers, said frame member being movable on said standard to bring said mangle into position within said chamber when said rollers are in upright position, and a door for closing said chamber connected with said frame member and movable into closed position when said mangle is within said chamber.

19. In combination, a structural body having a chamber therein, a door for said chamber, a frame plate connected with said door, and a pair of rollers mounted on said frame plate and movable into an operative position in which they project beyond said door and into an inoperative position in which they lie adjacent said door.

20. In combination, a door mounted to swing about an upright axis, a mangle secured to one face of said door and having rollers mounted to move into a horizontal position in which they project beyond said door and into parallel relation with said door adjacent one face thereof, one of said rollers being movable toward and away from

the other, and a foot lever for shifting said movable roller, said lever being foldable into a compact position adjacent the face of said door.

21. In combination, a structural body having a chamber therein, an upright standard positioned adjacent said chamber, a door hinged to said standard, a frame plate connected with one face of said door, a turn-table mounted on said frame plate for movement about a horizontal axis, a pair of mangle rollers secured to said frame plate, a motor mounted on said frame plate for driving said mangle rollers, one of said rollers being movable relative to the other, a lever for shifting said movable roller, a table for di-

recting material between said rollers, a basket for receiving said material from said rollers, said table and basket being foldable into compacted position relative to said rollers, and a pivotal support for said lever about which said lever is movable into a compacted position adjacent said door, said door being arranged to carry said mangle parts into said chamber when said parts are arranged in their compacted positions and said door is closed.

In testimony whereof I have signed my name to this specification on this 14th day of October, A. D. 1922.

JAMES W. MENEFEE.
